Design U.S. Appl. No. 29/627,256, filed Nov. 24, 2017, First Names Inventor: Hiromichi OHTA.

Primary Examiner — T Chase Nelson*Assistant Examiner* — Kelly L Gross(74) *Attorney, Agent, or Firm* — Oblon, McClelland, Maier & Neustadt, L.L.P.(57) **CLAIM**

The ornamental design for an orthosis, as shown and described.

DESCRIPTION

FIG. 1 is a front elevational view of an orthosis showing the new design.

FIG. 2 is a rear elevational view thereof.

FIG. 3 is a left side elevational view thereof.

FIG. 4 is a right side elevational view thereof.

FIG. 5 is a top plan view thereof.

FIG. 6 is a bottom plan view thereof.

FIG. 7 is a front view of the orthosis in use.

FIG. 8 is a rear view thereof; and,

FIG. 9 is a right side view thereof.

The broken lines in the drawings indicate the unclaimed portions of the orthosis and form no part of the claimed design. Additionally, the broken lines in the reference views also depict environment that forms no part of the claimed design.

1 Claim, 8 Drawing Sheets(56)
